UNITED STATES PATENT OFFICE.

THEODORE S. MORRISON, OF CHICAGO, ILLINOIS.

DAVENPORT BED.

Application filed August 14, 1924. Serial No. 731,977.

This invention relates to improvements in davenport beds and more particularly to davenports equipped with an extensible section whereby the same may be converted 5 into a bed for sleeping purposes.

The object of the invention is to provide an improved construction for davenports of the character described, in which simplicity of design may be combined with ease of 10 manipulation. A further object of the invention is to provide an improved arrangement of supporting members for the extensible bedforming section. Other objects of invention will appear from time to time as 15 the description proceeds.

The invention may best be understood by reference to the accompanying drawings illustrating one form in which it may be embodied.

20 In the drawings:

Figure 1 is a front view of a davenport constructed in accordance with my invention.

Figure 2 is a top plan view of the davenport with the seat portion extended, and with parts broken away to show the box and spring cover carried by the main frame.

Figure 3 is a side view in section showing the seat portion in extended position to 30 form a bed.

Figure 4 is a view similar to Figure 3, but with the seat portion in normal position to form a davenport.

Figure 5 is an enlarged fragmentary view 35 with telescoping side rails and adjacent parts shown in cross section.

The invention herein disclosed is applicable to the ordinary style of over-stuffed davenport for the purpose of converting the 40 same into a full sized bed. Davenports of this class are usually equipped with an extensible seat portion 10 slidably mounted in the main frame in such a way that it may be drawn forward its full width, as clearly 45 shown in Figures 2 and 3, to provide the additional width required for a bed, this being usually accomplished by using the detachable seat cushions, 11, 11 to fill the space normally occupied by the seat section 10. 50 It is also desirable to provide auxiliary supports for the extensible section, and heretofore such devices have been provided at or adjacent the front ends of the extensible section normally in raised position but provided with various mechanisms and devices 55 whereby they may be lowered into support-

ing contact with the ground when the section is extended.

In my improved davenport, I provide a novel arrangement of supports comprising 60 a pair of legs 12, 12, rigidly attached adjacent the front ends of the extensible section 10 so as to be movable therewith. Said legs are preferably adapted to conform with the general design of the davenport, and especially to harmonize in ornamental detail with the main supporting legs 13, 13, at the front ends of the main frame, so that when the extensible section is in normal position to form the davenport as shown in Figures 70 1 and 4, the auxiliary supports or legs 12, 12, on said section give the appearance of being an additional pair of supports for the main frame of the davenport intermediate 75 the corner legs 13, 13.

The frame construction of the davenport is shown in Figures 3, 4 and 5. The main frame consists of a front rail 21, a back rail 22, and side rails 23, 23. These members form a rectangular frame supported above 80 the floor level by rear legs 24, 24 and the front legs 12, 12, the latter being already referred to. Above the main frame members mentioned are the back and arm frame members which need not be especially referred to. 85

The extensible frame of seats section 10 consists of front and rear rails 26 and 27 and side rails 28, 28 rigidly connected together and suitably reinforced at the corners and braced throughout. The front rail 26 sets 90 in a recessed portion 29 in front of the rail 21 of the main frame, so that the seat section 10 becomes flush with the front of the main frame when the parts are in normal position shown in Figures 1 and 4. The 95 side rails 28, 28, are adapted to register with side rails 23, 23 of the main davenport frame and are slidably connected therewith. In the preferred form shown this slidable connection consists of a series of telescoping 100 members as for instance each of the side rails 28, 28 and 23, 23 are provided respectively with oppositely disposed dove-tailed grooves 30 and 31 in which grooves a single elongated sliding member 32 is fitted so as 105 to afford relative longitudinal telescoping movement of the three members. A stop 33 is arranged at the rear end of the upper rail 23 and moves in a registering slot 33^a in the member 32 while a similar stop 34 is arranged at the forward end of the lower rail 28 and moves in a similar slot 34^a, the 110

rangement being such that limited longitudinal movement is afforded between each of the upper and lower side members 28 and 23 with respect to the intermediate member 32. Thus when the extensible seat portion is withdrawn to its fullest extent as shown in Figure 3 the member 30 has engagement with both upper and lower members but in an intermediate position as shown. By 10 means of the telescoping sections as described, the seat section may be easily moved into and out of its extended position.

I find it preferable to arrange the auxiliary supporting legs 12, 12 carried by the 15 extensible seat section 10 so as to be raised slightly from the floor when the seat portion is in closed position as shown in Figures 1 and 4, and permitting the legs to come into supporting engagement with the 20 floor only when the seat section is extended. This result is obtained by providing sufficient play in the telescoping members so that the overhanging weight of the extensible section is sufficient to depress the legs 25 12, 12 into supporting engagement with the ground. This arrangement makes it easier to manipulate the sliding section and reduces wear on carpets, rugs or floors.

In davenport beds of this type heretofore constructed a front main frame member has ordinarily been provided to extend from one corner leg to the other while the extensible section moved over this lower frame member. In my improved form of 30 davenport it will be observed that the entire front surface of the davenport together with the rigid legs 12, 12, is movable with the seat section, but in the form shown the appearance of a solid frame member along the 35 bottom of the davenport is preserved by providing the main frame with a pair of frame members 35, 35 on opposite sides of the recessed portion 29 and in alignment with the front rail 26 of which fits in this 40 recessed portion when said section is in normally closed position. This arrangement gives the appearance of a rigid frame member having all four supporting legs attached thereto. It will be understood, however, that my invention may be applied to 45 other styles of davenports in which this lower frame member is not visible.

I further find it preferable to provide a 50 box or receptacle 40 for bedding or the like, located within the main frame and under the extensible section 10. As shown herein

this box comprises front and rear walls 41 and 42, end walls 43, 43 and bottom 44. By reason of the elimination of folding legs, and more or less complicated mechanism for 60 actuating the same, which heretofore occupied considerable space underneath both ends of the seat portion and main frame, I am enabled to make this box much longer at 65 its ends than heretofore. As shown in Figure 2, the box extends with its end walls 43, 43 to the side rails 23, 23 of the main frame. Heretofore such boxes have usually been provided with a solid cover hinged to the 70 main frame. In the improved form shown I provide a cover comprising a frame 45 hinged to the rear box wall 42 and having a 75 spring support 46 of the usual kind extending thereacross. It will be observed that the frame 45 and its spring extends with the box 40 substantially the entire length of the davenport seat so as to provide additional 80 comfort when the device is used as a bed. The frame 45 and spring 46 may also be provided with a fabric cover 47 to protect the bedding or other material in the receptacle from dust and dirt.

While I have illustrated and described one particular embodiment of my invention, it will be understood that I do not wish to 85 be limited to the exact construction shown and described, but that various changes and modifications may be made without departing from the spirit and scope of my invention. 90

I claim:

A davenport having a main frame and supporting legs adjacent the corners thereof, an upholstered seat portion, telescoping guide means at opposite ends of said seat portion permitting limited extension thereof substantially its own width forwardly of said main frame, a receptacle carried in fixed position on said main frame between and below said guide means and beneath 100 said seat portion, a removable cover for said receptacle hinged along the rear edge thereof, said frame having its sides formed of inverted L-shaped metal pieces extending vertically above said receptacle to a level 105 with the top of said telescoping guide means, and being provided with resilient spring means substantially flush with the tops of said L-shaped pieces extending thereacross.

Signed at Chicago this 5th day of August, 1924.

THEODORE S. MORRISON.
